(57) **CLAIM**

The ornamental design for a blood pressure monitor, as shown and described.

DESCRIPTION

FIG. 1 is a perspective view of a blood pressure monitor embodying our new design;

FIG. 2 is top view thereof;

FIG. 3 is bottom view thereof;

FIG. 4 is a side view thereof;

FIG. 5 is another side view thereof;

FIG. 6 is a front view thereof; and,

FIG. 7 is a back view thereof.

Broken lines, where shown, are used to illustrate portions of the blood pressure monitor that form no part of the claimed design.

The dot pattern areas represent areas of contrasting appearance. As shown in FIGS. 1-7, the dot pattern area on the bottom portion of the blood pressure monitor and the dot pattern area on the rounded, rectangular plate within the rounded, rectangular recessed portion on the top surface of the blood pressure monitor represent areas of contrasting appearance.
